UNITED STATES PATENT OFFICE.

LOUIS J. GROTH, OF PIQUA, OHIO.

DESIGN FOR AN IDENTIFICATION-TAG.

52,392.

Specification for Design. Patented Sept. 10, 1918.

Application filed May 25, 1917. Serial No. 171,034. Term of patent 7 years.

To all whom it may concern:

Be it known that I, LOUIS J. GROTH, a citizen of the United States, residing at Piqua, in the county of Miami and State of Ohio, have invented a new, original, and ornamental Design for Identification-Tags, of which the following is a specification, reference being had to the accompanying drawing, forming a part thereof.

The figure is a perspective view of an identification tag, showing my new design.

I claim:

The ornamental design for an identification tag, as shown.

LOUIS J. GROTH.
